UNITED STATES PATENT OFFICE.

MARCUS L. DE VOURLSEY, OF NEWARK, NEW JERSEY.

DESIGN FOR A CARRIAGE-LAMP.

SPECIFICATION forming part of Design No. 21,778, dated August 16, 1892.

Application filed February 11, 1892. Serial No. 421,111. Term of patent 7 years.

To all whom it may concern:

Be it known that I, MARCUS L. DE VOURLSEY, a citizen of the United States, residing at Newark, in the county of Essex and State 5 of New Jersey, have invented and produced a new and original Design for Carriage-Lamps; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

The accompanying drawings are deemed 15 sufficient to fully illustrate the design.

Figure 1 is a side elevation of the newly- 20 designed carriage-lamp, and Fig. 2 an enlarged plan of the top or upper portion.

The leading feature of the design consists 25 in the novel shape of the lamp. A indicates the body of the lamp, and B

the upper part. The lower part of the body is cylindrical at *a*, with enlarged ornamental members *b* at the top. Above said ornamental members the body is enlarged, as at *c*. 25 The head or upper part of the lamp is star-shaped in plan, the radiating projections having downward curves terminating in depending whirls or ornamental drops *f*. Above the star-shaped portion the lamp is spherical or 30 globular, or is head-like, as indicated at *d*.

What I claim as new is—

The design for a carriage-lamp, substantially as shown and described.

In testimony that I claim the foregoing I 35 have hereunto set my hand this 5th day of February, 1892.

MARCUS L. DE VOURLSEY.

Witnesses:

CHARLES H. PELL,
OSCAR A. MICHEL.
